UNITED STATES PATENT OFFICE.

FREDERICK R. SUNDEMAN, OF NEWBURGH, NEW YORK, ASSIGNEE TO SUNDEMAN SAFETY CARBURETER CORPORATION, OF NEWBURGH, NEW YORK, A CORPORATION OF NEW YORK.

CARBURETER.

1,208,227.

Specification of Letters Patent. Patented Dec. 12, 1916.

Application filed January 29, 1916. Serial No. 75,002.

To all whom it may concern:

Be it known that I, FREDERICK R. SUNDEMAN, a citizen of the United States of America, and a resident of Newburgh, county of 5 Orange, State of New York, have invented certain new and useful Improvements in Carbureters, of which the following is a specification.

My invention relates to carbureters having for their general object the vaporization of hydrocarbons.

The general object of my invention is to provide a device for producing an intimate uniform mixture of air and volatilized hydrocarbon, which mixture comprises the fuel mixture for an internal combustion engine.

My invention further consists in the novel arrangement and construction of parts, a preferred form of which is herein shown 20 and described, and my invention will be more particularly pointed out in the appended claims.

In the drawings, in which like characters indicate similar parts, Figure 1 is a longitudinal vertical section of a carbureter embodying my invention; Fig. 2 is a perspective view of the device shown in Fig. 1, with certain parts broken away; Fig. 3 is a view similar to Fig. 1, showing a modification; 30 and Fig. 4 is a partial plan view thereof.

The carbureter disclosed by the following description, taken in connection with the accompanying drawings, embodies the preferred form of my invention, and comprises 35 a float chamber of the well-known type for maintaining a constant hydrocarbon level in the carbureter and an open-ended passageway. One end of the passageway is controlled by a manually-operated throttle 40 valve. The other end of the passageway is controlled by a plurality of cooperating valves, and in the passageway a plurality of nozzles, which communicate with the constant-level chamber, discharge at different 45 levels.

Referring to Fig. 1, the constant-level chamber 1 receives fuel supply through the pipe 2, and a float 3 is connected to the lever 4, which is fulcrumed at 5 on the stud 6. 50 On the opposite side of the fulcrum from the float, the rod 7 is pivoted to the lever 4, and it cooperates with the ball check valve 8, which controls the admission of the hydrocarbon to the constant-level chamber in the 55 well-known manner. The open-ended pas-

sage 9 is attached to the constant-level chamber 1. One end of the passageway 9 is provided with flanges 10, whereby it may be connected to the intake manifold of an internal combustion engine. The opening 11 in the passageway is rectangular, and at the end near the flange coupling it is controlled by the butterfly throttle valve 12, mounted on the shaft 13, the movement of which is manually controlled by the lever 14, secured 60 thereon by the set-screw 15. A limiting member 16 is also secured to the shaft 13, and one of the ends of the limiting member cooperates with the lug 17 on the flange 10 to limit the opening movement of the butterfly valve, while the screw 18', passing through the other end of the limiting member 16 cooperates with the lug 17 to limit the closing movement of the butterfly valve 12. The inlet end of the passageway is controlled by the valve plates 18 and 19. The valve plate 18 is pivoted on a horizontal axis passing through its upper edge, so that its upper edge substantially contacts with the upper surface of the opening 11, and its 70 lower edge substantially contacts with the lower surface of the opening 11. The plate 18 extends substantially all the way across the opening, and the passageway is normally substantially closed by it. It is apparent 75 that suction formed in the passageway by the rotation of the engine will cause the plate 18 to swing about its axis, whereby its free end is lifted away from the lower surface of the passage. The swinging movement is controlled in two ways, shown respectively in Figs. 1 and 3. In the form shown in Fig. 1, the plunger 20 is guided in the cup 21, which is screw-threaded into the upper wall of the passageway and cooperates with the upper face of the plate 18. The cap 22 is threaded over the outside of the cup 21 and is locked in position by the nut 23. A collar 24 is secured onto the plunger 20, and a spring 25 is positioned between 80 the collar 24 and the cap 22. The tension of this spring may be varied by screwing the cap 22 down onto the cup 21 and locking it into position by the nut 23. The plunger 20 may be held in such a position that it does 85 not rest against the plate 18 when the plate is in normal position by undoing the screw 26 of the collar 27 and drawing the plunger upwardly within the collar and tightening the screw 26. It will be seen that when the 90

100

95

105

110

plunger is so adjusted, gravity alone will act to hold the plate 18 in normal position until the plate is swung upwardly far enough to contact with the end of the plunger 20.

In the form of valve-movement controller shown in Fig. 3, the plate 18 is provided with an extension 28, which has in it a slot 29, and passing through this slot is the threaded rod 30, which has a nut 31 positioned thereon. The other end of the rod 30 is pivoted to the limiting member 16 by the pin member 32. The nut 31 is positioned so that the plate 18 may swing to its normal position when the screw 18' is contacting with the lug 17; that is, when the throttle valve is in its limiting closed position. As the throttle valve is opened, however, the rod 30 will be moved so that the nut 31 will move away the extension 28 and permit the plate 18 to swing upwardly. Plate 18, therefore, can swing upwardly no more rapidly than the throttle valve opening will permit. The nut 31 can be adjusted so that there is lost motion in this controlling mechanism which will permit a certain opening of the valve 18 before the throttle valve is moved.

Leading from the constant-level chamber across the bottom of the passageway 9 there is a hydrocarbon conduit 33. Through the bottom of the passageway, and forming communication between the conduit 33 and the opening 11 of the passageway, there are a plurality of openings, through which extend nozzles 34. These nozzles are held in position by threaded members 35, co-operating with the threaded portions formed within the conduit. It is thus possible to adjust the elevation of these nozzles by removing the screw plugs 36 which are positioned in the bottom of the conduit. One of the nozzles 34 discharges at the same level at which hydrocarbon is maintained in the constant-level chamber, and another nozzle discharges in the passage at a higher level. Any number of these nozzles may be employed as is found desirable.

A screen 37 is positioned in the passageway, in the form shown in Figs. 1 and 3. The ordinary priming device 38 is provided for sinking the float to raise the level in the constant-level chamber for starting.

When the butterfly valve is almost closed and the engine is rotating slowly, a small volume of fuel mixture is drawn into the engine, and, therefore, a small volume of air will be drawn into the open end of the passageway. This will cause the valve plate 18 to open very slightly. As the speed of the engine increases, the valve 18 will be raised, and will direct the entering stream of air across the lowered nozzle, drawing gasoline from it in the well-known manner. As the throttle is opened wider, and the speed of the engine is increased, the valve 18 will be

swung up toward the horizontal position, thereby directing air across whatever nozzles are positioned so that they discharge at a higher level than the nozzle which discharges at the level of the hydrocarbon in 70 the constant-level chamber. It will thus be seen that as a greater amount of air is drawn in, a greater amount of hydrocarbon is added to the mixture. Of course, it is apparent that the variation of the vacuum in 75 the passageway and in the velocity of air across the nozzles will vary the amount of hydrocarbon drawn from them, so that, even though there are substantial differences between the discharge levels of the nozzles, 80 there will be a uniform increase in and discharge of hydrocarbon into the entering air stream, for the effectiveness of the nozzles will vary as the lower edge of the plate 18 approaches the level of their discharge 85 points.

The drops of hydrocarbon which are not vaporized by contact with the air will be forced against the screen 37 and disintegrated, and the volatilization of the hydrocarbon will be complete before it passes 90 the butterfly valve. In order that the inflow of air into the passage may be under the absolute control of the engine operator, the plate 19 is pivoted to rotate about a horizontal axis near the lower face of the opening 95 11, which axis passes through one edge of the plate. The control lever 39 for this plate extends outside of the passageway 9 and is adapted to have a link or rod connected to it which may be conveniently 100 reached by the engine operator. Whenever the engine is operating, the amount of air entering the passageway may be controlled by swinging the plate 19 counter-clockwise about its axis. When the engine is to be 105 started, this plate is swung about its axis until it engages the plate 18 in the form of device shown in Fig. 3, and is rotated in the form of device shown in Fig. 1 even after it engages the plate 18, namely, until it forces the plate 18 to a horizontal position. It will be seen that, under these circumstances, the air supply is substantially cut off, and a very great suction will be exerted upon the hydrocarbon nozzles and a very rich mixture 110 will be drawn into the engine for starting.

In the embodiment of my invention herein disclosed, it will be noted that the hydrocarbon nozzles discharge at different levels in a transverse plane, passing through the passageway at a point substantially adjacent that at which the plate 18 normally contacts with the lower surface of the passageway. As the amount of air drawn through the passageway varies, the plate 18 rises and falls, thereby changing the area of the free inlet opening. The action of gravity and of the spring 25 retards the rise of the plate 18, so that the vacuum in the passageway increases as the speed of the 115 120 125 130 135 140 145 150 155 160 165 170 175 180 engine increases, thereby increasing the flow of hydrocarbon into the entering air stream. As the plate rises and falls, it directs the entering air stream over more or fewer hydrocarbon nozzles, and also tends to keep the velocity of the entering air stream constant.

While I have described a particular embodiment of my device with great detail, I do not intend that my invention shall be limited to the specific features described, but intend that my invention shall include such modifications, adaptations and variations as may occur to those skilled in the art, and that it shall be defined by the hereunto appended claims.

What I claim and desire to secure by Letters Patent of the United States is the following:

1. In a carbureter, the combination of a horizontal open-ended passageway, a hydrocarbon chamber, a plurality of hydrocarbon nozzles communicating with said chamber and discharging within said passageway at different levels, an air admission valve hinged at its upper end in advance of said nozzles and normally inclined downwardly toward the nozzles and having its free end terminating short of the nozzles so as to swing up and down free thereof and acted upon directly by suction to be swung inwardly and upwardly by increased suction to direct the incoming air in a converging current upon one or more of the nozzles and to uncover one or more nozzles to the current of air depending upon the height that the valve is lifted, and a throttle valve controlling the flow of hydrocarbon fuel through said passageway to the engine.

2. In a carbureter, the combination of a horizontal open-ended passageway, a hydrocarbon chamber, a plurality of hydrocarbon nozzles communicating with said chamber and discharging within said passageway at different levels, an air admission valve hinged at its upper end in advance of said nozzles and normally inclined downwardly toward the nozzles and normally closing said passageway to prevent any substantial admission of air past the valve when the same is in its lowest position and having its free end terminating short of the nozzles so as to swing up and down free thereof and acted upon directly by suction to be swung inwardly and upwardly by increased suction to direct the incoming air in a converging current upon one or more of the nozzles and to uncover one or more nozzles to the current of air depending upon the height that the valve is lifted, and a throttle valve controlling the flow of hydrocarbon fuel through said passageway to the engine.

3. In a carbureter, the combination of a horizontal open-ended passageway of rectangular cross-section, a rectangular air admission valve near the inlet end of the pas-

sageway hinged at its upper end at the top portion of the passageway and extending downwardly and inwardly, a rectangular throttle valve within the passageway for controlling the flow of fuel mixture from the passageway to the engine, a hydrocarbon chamber, a plurality of hydrocarbon nozzles communicating with said chamber and discharging into the said passageway at different levels and at points between the free edge of said air inlet valve and the throttle valve, said air inlet valve being acted upon directly by suction to be swung inwardly and upwardly by increased suction so as to uncover one or more nozzles to the current of air depending upon the height to which the valve is lifted.

4. In a carbureter, the combination of a horizontal open-ended passageway of rectangular cross-section, a rectangular air admission valve near the inlet end of the passageway hinged at its upper end at the top portion of the passageway and extending downwardly and inwardly, a rectangular throttle valve within the passageway for controlling the flow of fuel mixture from the passageway to the engine, a hydrocarbon chamber, a plurality of hydrocarbon nozzles communicating with said chamber and discharging into the said passageway at different levels and at points between the free edge of said air inlet valve and the throttle valve, said air inlet valve being acted upon directly by suction to be swung inwardly and upwardly by increased suction so as to uncover one or more nozzles to the current of air depending upon the height to which the valve is lifted, a housing on the top of the passageway, a plunger extending slidably through said housing into the passageway in position to be engaged by the air valve when the latter is lifted by suction, and a spring within the housing and cooperating with the plunger to oppose the upward movement of the air valve.

5. In a carbureter, the combination of a horizontal open-ended passageway of rectangular cross-section, a constant level hydrocarbon chamber, a plurality of hydrocarbon nozzles communicating with said chamber and projecting upwardly in the passageway from the floor thereof, one of said nozzles being of substantially the height of the hydrocarbon level of the chamber and the other nozzle being substantially higher so as to require much higher suction in the passageway to draw hydrocarbon therethrough, an air admission valve rectangular in cross-section and hinged at its upper end at the top portion of the passageway in advance of the nozzles and extending downwardly and inwardly toward the base of the nozzles and in close proximity thereto, said air inlet valve being acted upon directly by the suction of the

5 engine to swing inwardly and upwardly to direct incoming air against the discharge openings of one or more of said nozzles depending upon the height to which said valve is lifted and a rectangular throttle valve in said passageway for controlling the flow of hydrocarbon fuel therefrom.

6. In a carbureter, the combination of a 10 horizontal open-ended passageway of rectangular cross-section, a rectangular air admission valve near the inlet end of the passageway hinged at its upper end at the top portion of the passageway and extending downwardly and inwardly to normally close 15 the passageway, a rectangular throttle valve within the passageway for controlling the flow of fuel mixture from the passageway to the engine, and a hydrocarbon chamber extending below the bottom of said horizontal passageway and parallel therewith, a plurality of hydrocarbon nozzles communicating with said chamber and discharging into the said passageway at different levels and at points between the free 20 edge of said air inlet valve and the throttle valve, said air inlet valve being acted upon directly by suction to be swung inwardly and upwardly by increased suction so as to uncover one or more nozzles to the current 25 of air depending upon the height to which the valve is lifted, and when closed preventing any substantial flow of air into the passageway.

7. In a carbureter, the combination of a 30 horizontal passageway, a hydrocarbon chamber, a conduit extending from said chamber transversely of and beneath the passageway and communicating with the chamber, a plurality of hydrocarbon nozzles communicating with said conduit and extending into the passageway and discharging at different heights therein, an air admission valve hinged at one end in the passageway in advance of said nozzles and normally inclined 35 toward the nozzles and having its free end terminating short of said nozzles and acted upon directly by suction to be swung inwardly by increased suction to direct the incoming current of air against one or more 40 of the discharge openings of said nozzles depending upon the degree to which the valve is swung.

8. In a carbureter, the combination of a 45 horizontal open-ended passageway of rectangular cross-section, a rectangular air admission valve near the inlet end of the passageway hinged at its upper end at the top portion of the passageway and extending downwardly and inwardly, a hydrocarbon chamber extending below the bottom of the passageway, and a conduit extending from said chamber transversely of and beneath the passageway for the flow of hydrocarbon from the chamber, a plurality of 50 nozzles communicating with said conduit

and extending into the passageway and terminating at different heights, said air admission valve being acted upon by suction to be swung upwardly and inwardly to uncover one or more of said nozzles depending upon the height to which it is lifted, and a throttle valve in the passageway controlling the flow of fuel to the engine. 70

9. In a carbureter, the combination of a horizontal passageway, a hydrocarbon chamber, a conduit extending from said chamber transversely of and beneath the passageway, said conduit having passages extending transversely thereof and communicating therewith and adapted to receive nozzles inserted from beneath, nozzles inserted in said passages and extending upwardly therefrom into the passageway, removable plugs closing said transverse passages, an air admission valve hinged at its upper end in said 80 passageway on the air inlet side of said nozzles and adapted to be acted upon by suction to increase the air inlet opening and uncover one or more of said nozzles according to the increase in suction, and a throttle valve in 85 said passageway controlling the flow of hydrocarbon fuel from the same to the engine. 90

10. In a carbureter, the combination of an open-ended passageway, a manually operable valve controlling the open end of said 95 passageway, a hydrocarbon nozzle in said passageway, and valve mechanism controlling the entrance of air at the other end of said passageway, comprising a suction-operated member and a manually-operated member 100 co-operating therewith to substantially close said last-named open end while said suction-operated member is in any position.

11. In a carbureter, the combination of an open-ended passageway, a manually operable 105 valve controlling one open end of said passageway, a hydrocarbon nozzle in said passageway, and valve mechanism controlling the entrance of air at the other end of said passageway, comprising a swinging suction-operated valve plate, and means comprising 110 a lost motion connection connecting said manually-operated valve with said suction-operated valve, whereby the extent to which the suction-operated valve may be moved to 115 increase the air inlet is limited by the position of the manually-operated valve.

12. In a carbureter, the combination of a horizontal open-ended passageway, a hydrocarbon chamber, a plurality of hydrocarbon 120 nozzles communicating with said chamber and discharging within said passageway at different levels, an air admission valve hinged at its upper end in advance of said nozzles to swing up and down and acted 125 upon directly by suction to be swung inwardly and upwardly by increased suction to direct the incoming air in a converging current upon one or more of the nozzles depending upon the elevation of the valve, and a 130

throttle valve controlling the flow of hydro-carbon fuel through said passageway to the engine.

13. In a carburetor, the combination of a horizontal open-ended passageway, a hydro-carbon chamber, a hydrocarbon nozzle communicating with said chamber and discharging within said passageway, an air admission valve in the passageway hinged at its upper end in advance of said nozzle and normally inclined downwardly toward the nozzle and acted upon directly by suction to be swung inwardly and upwardly by increased suction to direct the incoming air in a converging current upon the nozzle and vary

the air inlet opening depending upon the height that the valve is lifted, a manually-operated device in said passageway operatively related to said valve to engage the same to restrict the air inlet opening normally controlled responsive to suction, so as to effect increased suction on the nozzle at the will of the driver as in starting, and a throttle valve controlling the flow of hydro-carbon fuel from said passageway to the engine.

In testimony whereof, I have signed my name to this specification.

FRÉDERICK R. SUNDERMAN.
